AUTOMATIC GOLF BALL TEEING DEVICE

Leonard Gale, Washington, D. C., assignor to
Frederick Klein, New York, N. Y.

Application July 11, 1944, Serial No. 544,364

10 Claims. (Cl. 273—33)

This invention relates to improvements in golf ball teeing devices for use in the practice of driving golf balls, and more specifically to such a device which is automatic in its action.

I am aware of various golf ball teeing devices heretofore patented and which to my knowledge have never been successfully commercialized, due in part to defects in structure which will not withstand exposure to the elements and shocks to which the device is subjected by a golf club when striking a ball from the tee; also, such teeing devices require some disconcerting manual act on the part of a golfer, either foot or hand actuated to cause a ball to be teed up. It is therefore the primary object of this invention to provide a gravity operated golf ball teeing device which is automatic in its action in that it does not require motor or other outside power other than the weight of the golf balls to effect operation, that is, a golf ball is automatically teed up after a previously teed golf ball has been driven from the tee, thus a golfer may assume a standing position relative to the tee and successively drive golf balls therefrom without altering his or her foot position and with continuous mental concentration upon the striking of the ball rather than experiencing disconnecting interruptions which occur in manually actuated teeing devices.

Another feature of the invention resides in an automatic golf ball teeing device in which the working parts thereof are enclosed and protected against the elements and against damage by striking contact of the golf club, the only exposed part being a rubber tee member which "gives" as the head of the golf club follows through during the striking of a golf ball therefrom.

A further feature of the invention is the provision of an automatic golf ball teeing device which is rapid in its action in presenting a golf ball to teed position after a previously teed golf ball has been driven from the tee, thus expediting the play which is psychologically beneficial to the practicing golfer, and financially advantageous to the proprietors of golf practice driving ranges and professional golf instructors when the device is installed at public golf driving ranges and private golf courses respectively.

Whereas I have set forth some of the outstanding features of my invention, other novel features will become apparent as the following specification is read in conjunction with the accompanying drawings, in which:

Figure 1 is a side elevational view with parts in section, illustrating the parts in ball teeing position.

Figure 2 is an enlarged vertical longitudinal sectional view with the ball supply magazine removed, the parts being illustrated in ball teeing position.

5 Figure 3 is a top plan view of the ball feeding end of the device with the parts in the position illustrated in Figure 2.

Figure 4 is a top plan view of the ball teeing end of the device with the parts in the position illustrated in Figure 2.

10 Figure 5 is an enlarged detail vertical sectional view on the line 5—5 of Figure 4, with a portion of the lever elevator broken away and in section.

Figure 6 is an enlarged detail vertical sectional view substantially on the line 6—6 of Figure 4.

15 Figure 7 is an enlarged vertical transverse sectional view on the line 7—7 of Figure 2.

Figure 8 is a vertical longitudinal sectional view illustrating the position of the parts just prior to the upward movement of the tee member to tee position.

20 Figure 9 is a top plan view of the ball feed release with the parts in the position illustrated in Figure 8.

25 Referring to the drawings by reference characters, the numeral 10 designates my improved golf ball teeing device in its entirety which includes a substantially L-shaped casing composed of a horizontally disposed base casing 11 having a removable cover for housing the ball teeing mechanism 12 and a vertical casing 13 which is substantially elliptical in cross section and closed at its top by a hinged cover 14. The vertical casing 13 is composed of an upper casing section 15 which houses a spiral ball runway 16 and combined with the casing section 15 provides a golf ball magazine. The lower outlet end of the spiral runway opens onto a downwardly inclined platform 17 provided within and disposed at the top of the lower section 18 of the casing 13. The platform 17 includes a ball receiving station 19 at one end, a ball discharge chute 20 at the other end, and an intermediate ball releasing station 21 therebetween. A double acting gate control is provided for the passage of a golf ball

30 A from the station 19 to the station 21, and for the passage of a golf ball B from the station 21 to the discharge chute 20 (see Figure 3). This double acting gate control includes a shaft 22 mounted in bearing ears 23 depending from the platform 17. Fixed to the shaft 22 is a U-shaped member 24, the legs of which constitute gates or stop blades 25 and 26 which extend through slots 27 and 28 respectively provided in the platform

35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965

radial angles, the gate 26 normally extending vertically to be in the path of the ball B whereas the gate 25 extends forwardly to normally be disposed out of the path of the ball A. The movement of the gate 25 is on a plane intermediate the ball receiving station 19 and the ball receiving station 21 whereby actuation of the member 24 by an upward push upon the depending arm 29 formed as an extension of the shaft 22 will cause the gate 26 to move rearwardly out of the path of the ball B to release the same onto the chute 20 and will simultaneously cause the gate 25 to swing upwardly into a position to obstruct the passage of the ball A, however, upon the release of the upward push on the arm 29, the same will drop, permitting the gates 25 and 26 to return to their normal positions, whereupon the ball A is permitted to roll to the dispensing station 21, since the ball B has rolled to the chute 20, and the station 19 has received the next lowest ball C from the golf ball magazine. The arm 29 is actuated by the golf ball teeing mechanism 12 now to be described and the ball B which has been released is picked up and conveyed to the tee end of the device. The platform 17 at the ball receiving station 19 is upwardly inclined from the rear wall of the casing section 18 to cause the ball to roll thereagainst, whereas guide walls 30 confine the ball as it enters the releasing station 21 and during its passage down the chute 20.

Contained within the base casing 11 is a rectangular shaped frame 31 which supports an inclined trough shaped ball runway 32 by means of hanger brackets 33. The rear high end of the runway 32 is disposed in vertical alignment with the ball discharge chute 20 and terminates short of the rear end wall of the casing 11. The lower or discharge end of the runway 32 terminates short of the front end wall of the casing 11, and the bottom wall of the same at the discharge end is provided with a trip plate 34 having its rear end connected to the bight portion of a substantially U-shaped cradle member 35 which has its upstanding arms pivoted to the sides of the runway as at 36. Also attached to the member 35 and extending rearwardly therefrom is a counter-balance weight arm 37 which acts to normally swing the trip plate 34 upwardly, while the weight of the next ball D to be teed acts to hold the trip plate 34 down by reason of its weight overbalancing the counter-weight arm 37. When the trip plate is down, it rests upon a fixed horizontal offset seat 38 formed on a bracket 39 secured to one side of the frame 31. An arm 40 extends forwardly from one of the arms of the cradle member 35 and the free end thereof is provided with an elongated slot 41 which slidably receives a pivot pin 42 secured to the rear end of an angular rock arm 43 which is pivoted intermediate its ends to the bracket 39 as at 44. When the trip plate 34 is up by reason of its being free of the weight of a ball, the front end of the rock lever assumes a substantially horizontal position for preventing the release of the tee lifting mechanism from a raised teeing position to a lowered ball pick up position which will be fully explained hereinafter.

The ball D is releasably held upon the inclined trip plate 34 until such time as it is to be released by a wire gate member 45, having a transverse shaft portion 46 journaled in bearings 47 at the lower end of the runway 32. The gate member 45 extends along the outer side of the runway

and has an inwardly extending finger 48 which when the gate is down, is disposed in the path of the ball D and it normally rests upon the outer side wall of the runway as best seen in Figure 2. An L-shaped actuating arm 49 extends from the inner end of the shaft portion 46 and is disposed in the path of downward movement of a fulcrumed lever presently to be described. The gate member 45 overbalances the rearwardly extending actuating arm 49 so that the normal position of the gate member is down in ball obstructing position.

Pivoted or fulcrumed intermediate its ends within the frame 31 as at 50, is a rock lever 51, the same being off center and overbalanced at the front head end 52 thereof. The front head end 52 of the lever 51 is constructed of a straight channel piece whereas the tail end 53 is substantially U-shape and constructed of lighter tubular material. The head end 52 normally overbalances the tail end 53 although it is much shorter in length for I utilize the leverage under the weight of a ball picked up by the tail end to overbalance the head end in spite of the fact that the head end is also under the weight of a golf ball to be lifted to teeing position. By making the tail end 53 U-shape, the center of gravity of the same is disposed below the pivotal axis of the lever. An overthrow spring 54 is located at the pivotal axis of the lever and has one end attached thereto and its other end secured to a fixed bracket 55. The spring 54 is thrown past center in favor of the head end of the lever when the head end moves downwardly and the tail end moves upwardly as illustrated in Figure 8.

The rock lever 51 functions as a ball elevator device for the reason that the tail end 53 delivers a ball from the platform 17 to the top of the runway 32, while the head end 52 thereof lifts a released ball from the lower discharge end of the runway to a teed position above the top of the casing 11. The rock lever 51 is disposed beside the runway 32 and fixed to the inner side of the head end 52 is a U-shaped bracket 56 to which the arms of a U-shaped cradle member 57 are pivoted as at 58. The cradle member 57 is pivoted off center and has a weighted tail 59 extending in a direction toward and disposed beneath the lever 51 with which it contacts to limit the counter-balancing of the weight of a tee 60 and ball E supported by the cradle member. The tee 60 includes an inverted U-shaped base 61 pivotally mounted on a shaft 62 mounted in the opposed side arms of the cradle member 57, and the tee member is held in a position normally perpendicular to the cradle member by a coil spring 63 mounted on the shaft 62, one end of which bears against the bridge portion of the inverted U-shape base member while the other end of the spring is bent laterally and extends beneath the bottom edge of an adjacent ear of the base member and which projects therebeyond to be disposed in the path of the adjacent lower edge of the arm of the cradle member to engage the same when the tee member 60 is upset to the dotted position illustrated in Figure 7 caused by the head of a golf club striking the tee member as the ball E is struck therefrom. Secured to the bridge portion of the inverted U-shaped base 61 is a solid block 64 which is telescoped by the lower end of a short rubber tubular tee 65, the open top of which receives and supports the ball E in teed position. A clamp 66 encircles the lower end of the tubular tee 65 and secures it to the block 64. The tee member 60 is therefore mov-

able up and down with the head end of the lever 51, and is disposed relative to the discharge end of the runway 32 so as to receive the ball D when the head end of the lever is down and the gate 45 is lifted by reason of the head end of the lever striking and depressing the actuating arm 49. The top wall of the casing 11 is provided with an opening 67 for the passage of the tubular tee 65 and ball E as the head end 52 of the lever 51 moves upward to ball teeing position.

For preventing the ball E from accidentally rolling off the tubular tee 65 during the upward movement of the head end 52 of the lever 51, I provide a wire guard member 68 which has its inner end bent to provide an angular offset portion 69, and a transverse shaft portion 70 journaled in bearings 71 at a point directly above the sides of the channel head end 52. A tail piece 72 extends rearward beyond the axis of the shaft portion 70 and is disposed in the channel of the head end 52 to limit upward swinging movement of the guard member relative to lever 51 as illustrated in Figure 8. A spring 73 surrounds the shaft portion 70 and has one of its ends fixed to the channel head end 52 of the lever while its other end bears against the underside of the offset portion 69 to impart a normal upward movement of the guard member, which movement is limited upon downward movement of the head end 52 of the lever by the tail piece striking the bottom of the channel from which the head end 52 is constructed. The front free end of the guard member is provided with a substantially right angularly bent guard finger 14 which is curved to accommodate the curvature of the ball E. As the head end of the lever 51 rises upwardly, and as the ball E passes through the opening 67, the finger guard strikes the top wall of the casing 11, but at that time the tubular tee 65 has assumed a vertical position sufficient to complete the teeing of the ball E without fear of the ball accidentally rolling from the tee 65. A vertical guide wire 14' cooperates with the guard member 68 for preventing accidental unseating of the ball E from the tubular tee 65 during its upward movement.

For releasably latching the head end 51 of the lever in a raised position when moved thereto with the ball E supported upon the tee 65, I provide an arm 75 pivoted at its top as at 76 to a fixed bracket 77 and which is yieldably held in a substantially vertical position (Figure 5) by a spring 78, a fixed stop 79 being provided to limit forward movement of the arm. Pivoted to the lower end of the arm 75, as at 80, is a releasable catch member 81 having a shoulder 82 on the front edge normally disposed in a horizontal position by the action of a spring 83 carried by the pivot 80. The spring 83 tends to normally turn the catch 81 to move the shoulder upwardly, which movement is limited by the catch striking a stop shoulder 84 fixed to the arm 75. The shoulder side of the catch may be pushed down to releasing position against the action of the spring. The front edge of the catch has an inclined cam surface 85 to be engaged by the angular foot 86 of a pendant leg member 87 formed integral with and depending from the cradle member 57, as the tee member 60 moves upward from its lower ball pick up position to raised ball teeing position, at which time the arm 75 swings rearwardly to enable the foot 86 to rise to a level to seat upon the shoulder 82. However, due to the fact that the weight of the ball E overbalances the counter-balance weight 59

the leg is held in the path of the catch 81, but should the tee member 60 move upwardly without the weight of a ball thereon, the counter-balance weight 59 rocks the cradle to cause the foot 86 to be disposed out of the vertical plane and path of the catch 81, whereupon the tee member 60 will not become latched in raised position. The foot 86 becomes released from the shoulder 82 by the tilting or swinging movement of the leg member 87 when the ball E is struck from the tee 65, however, it will not release unless the ball D is in position upon the trip plate 34 which serves to lift the rock arm 43 out of the path of releasing swinging movement of the foot. Should a ball fail to reach the discharge end of the runway 32 before a ball is hit, rock arm 43 will move to a position to obstruct the lateral movement of the foot 86 to a position clear of the shoulder 82, but when the next ball to be teed eventually reaches the discharge end of the runway 32, the weight of the same causes the rock arm 43 to move out of the path of the foot 86, whereupon the foot may move laterally and the head end 52 of the lever 51 moves down to pick up the next ball D to be teed.

The tee or head end 52 of the lever 51 will remain down should it reach its lowered ball pick up position and the lower end of the runway is empty of the ball D, for under such conditions, the foot 82 engages beneath a spring catch 88 carried by a fixed bracket 89 (Figure 8). The weight of a ball E supported upon the tee member 60, rocks the same to cause the foot 82 to clear the catch.

The tail end 53 of the rock lever 51 supports a ball basket 90 comprising an inclined bottom wall 91, side walls 92-92 and a front wire gate 93 having a right angularly disposed shaft portion 94 pivoted to a pair of spaced bearing ears 95 mounted on an inwardly extending portion of the bottom wall 91. The free end of the wire gate 93 is curved downwardly to normally rest upon the forwardly extending portion of the bottom wall 91 and also projects therebeyond into the path of an upstanding lug 96 on the frame 31 to cause the gate to lift up to release a ball from the basket and permit it to roll by gravity onto the upper end of the runway 32 as best illustrated in Figure 2. The ball basket 90 also carries a finger 97 disposed in the path of the arm 29 so as to strike the same and swing it upward to move the gate 25 to open position and simultaneously move the gate 26 to ball obstructing position whereby to release ball B and hold ball A in check until the arm 29 is released by the finger 97 as the basket moves down under the weight of the ball B and the leverage of the tail end of the lever.

For initially feeding golf balls from the magazine 13 to the platform 17, I provide a vertical plunger 98 slideable in a central bearing 99 rising upwardly through the casing section 15 about which the spiral ball runway 16 winds. The top end of the plunger is provided with a head 99' and interposed between the head and the bearing is an expansion spring 100 acting to normally hold the lower end of the rod directly above a lip 101 fixed to and extending from the member 24. Assume that the last golf ball of a supply of 70 golf balls has been fed to the lower end of the runway 32 and which ball is released to the tee 65 which remains down because there is no ball in the magazine or upon the platform 17 which may be fed to the basket 90 to depress the tail 76 end of the lever 51 and lift the head end. The

attendant may restock the ball magazine, but the lowermost ball can only roll to station 19 on the platform 17, where the gate 25 is blocking its passage to the releasing station 21. The attendant or operator must press the plunger 98 down to cause the lower end to depress the tongue 101 which causes the gate 25 to move out of the path of the ball A which enables the ball A to move to station 21 (Figure 9), and ball C to move to a position formerly occupied by ball A. The operator releases the plunger whereupon the position of the gates 25 and 26 return to their former position which permits ball A in Figure 9 or ball B in Figure 3 to roll into the basket 90 which overbalances the head end of the rock lever, deposits a ball at the top of the runway, which ball rolls down and becomes ball D. Thus, the balls essential to the operation of the device are now in position, balls A and B are at their respective stations 19 and 21, ball D is at the end of the runway 32, and ball E is in teed position, and it is from this operative position of the device that a description of a cycle of operation will be given.

In use, the casing 11 is embedded in the ground, so that the top of the casing is flush with the surface of the ground. Assume that the parts of the apparatus are in the position illustrated in Figures 1, 2, 3, 4, 5, 6, and 7, whereupon the ball E is in teed position upon the tee 65, the next ball to be teed designated D is at the low end of the runway 32 and is held back by the gate 45, the tail end 53 of the lever 51 is in down position and the balls A and B are at their respective stations 19 and 21. The golfer takes a position forward of the device and with the use of a golf club, proceeds to drive the ball E from the tee member 65. Should the club head contact the tee 65, it may be upset without damage to the mechanism as illustrated in dotted lines in Figure 7, and automatically return to an upright position by the action of the spring 63. As the weight of the golf ball E was instrumental in overbalancing the cradle 57 to cause the foot 86 of the arm 87 to engage and rest upon the shoulder 92 of the catch 81, it will be understood that the absence of a ball upon the tee 65 causes the weight 59 to rock the cradle member 57 to cause the foot 86 to move laterally out of the path of the catch 81, whereupon the head end of the lever 52 which overbalances the tail end 53 starts downward, and as the lever 51 rocks, the spring 54 moves past center and assists the head end 52 in its downward movement. In the course of downward movement of the head end 52 of the lever, the same strikes the actuating arm 49 causing the gate 45 to be lifted upwardly to move the finger 48 of the gate out of the path of the ball D, and at which time the tee 65 has moved down to a position adjacent the discharge end of the chute to receive the ball D which becomes the next ball to be teed. Also during the downward movement of the head end of the lever, the guard member 68 has moved to the position shown in Figure 8, where the portion 74 thereof acts to confine the ball and prevent it from rolling off the tee 65, for the tee at this time assumes a tilting angle as shown in Figure 8. As the head end of the lever moves downwardly, the tail end 53 moves upwardly, during which time the finger 97 has engaged the actuating arm 29 to cause the gate 26 out of the path of the ball B and the gate 25 to move to an obstructing position relative to the ball A. As the ball B is released, it rolls by gravity down the inclined discharge chute 20 and into the basket 90. Due to the weight of the ball

in the basket and by utilizing the leverage of the tail end 53 of the lever 51, the tail end moves downwardly, while the head end moves upwardly. As the basket nears the limit of its downward movement, the free end of the wire gate 93 strikes the upstanding lug 96, causing the gate 93 to move upwardly and release the ball now present in the basket, the said ball rolling onto the runway 32 and coming to a stop at the lower end thereof against the finger 48 of the gate 45, for as the head end of the lever has moved up, it has released the actuating arm 49 whereupon the gate has dropped to ball obstructing position. As the tee member 60 moves upwardly with the weight of the ball upon the tubular tee 65, the foot 86 rides against the bevel or cam face 85 of the catch 81, and which contacting of these parts causes the spring pressed arm 75 to swing rearwardly to permit the leg 86 to move upwardly to a position to engage the shoulder 82 of the catch, whereupon the tee member 60 is held in raised position until such time as the ball supported by the tubular tee 65 is driven therefrom, and in which case the cycle of operation is repeated. In the event that the supply of balls in the magazine is exhausted and the last ball present at the lower end of the runway has rolled onto the tee member 65, the head end of the lever will remain down for there is no ball which may enter the basket 90 to overbalance the head end of the lever, and which stopping of the device indicates that the magazine should be stocked with a supply of golf balls. It will thus be understood that as long as the supply of golf balls is present in the magazine, the device will operate as each ball is driven from the tubular tee 65. There are no foot pedals, hand operated levers, or electric motor switches, for the golfer to operate in order to successively present the golf balls to teed position, thus eliminating the mental hazard which is present in the manually operating teeing devices heretofore patented.

While I have shown and described what I consider to be the most practical embodiment of my invention, I wish it to be understood that such changes in construction and design as come within the scope of the appended claims may be resorted to if desired.

Having thus described the invention, what I claim as new and desire to secure by Letters Patent of the United States is:

1. In a golf ball teeing device, a stationary inclined ball runway, a golf ball tee member normally disposed at the lower end of the runway to receive a golf ball as it rolls therefrom, a magazine for golf balls, gravity actuated means for delivering a golf ball from the magazine to the upper end of said runway, means responsive to the actuation of the gravity actuated means for raising the golf ball tee member to a raised tee position, and latch means operatively associated with the tee member and operatively responsive to the weight of a ball supported thereby for securing the tee member in tee position upon its upward movement thereto.

2. In a golf ball teeing device, a stationary inclined ball runway, a gate member at the lower end of the runway against which the next ball to be teed is adapted to abut, a golf ball elevator tee member movable upwardly to a raised tee serving position and downwardly to a lowered ball pick-up position adjacent the low end of the runway, means acting to normally move the tee member to lowered ball pick-up position, means operable upon the downward movement

of the tee member for opening the gate to permit the next ball to be teed to roll from the runway onto the tee member, a magazine for golf balls, means for automatically delivering a golf ball from the magazine to the upper end of the runway, means responsive to the actuation of the ball delivery means for raising the tee member to tee serving position and for permitting the gate to return to closed position to halt the rolling movement of the ball so delivered, and releasable latch means operatively associated with the tee member and operatively responsive to latching position under the weight of a golf ball supported thereby for securing the tee member in tee serving position, and operable to releasing position when the tee member is relieved of the weight of the golf ball after the same has been knocked therefrom to permit the tee member to move to lowered position under its lowering means to automatically repeat the cycle of operation of the device.

3. In a golf ball teeing device as set forth in claim 2, including a releasable means for preventing unlatching of the releasable latch means upon the absence of a ball at the low discharge end of the chute.

4. An automatic golf ball teeing device including an inclined runway, a normally closed gate at the low end of said runway against which the next ball to be teed is adapted to abut, a rock lever having a normally overbalanced head end and a tail end, a golf ball tee member carried by the head end of the rock lever, a golf ball basket carried by the tail end of the rock lever, a golf ball magazine, means operable upon the downward movement of the head end of said rock lever for opening said gate to enable a ball from the runway to pass onto said tee member, means operable upon the upward movement of the tail end of said rock lever for releasing a single golf ball from the magazine for reception in said basket for overbalancing the head end of said rock lever to move the tee member to raised tee position, means operable upon the down movement of the tail end of the rock lever for releasing a ball therefrom onto the high end of the runway for passage therewith to the gate, and means responsive to the weight of a golf ball on the tee member when in raised teed position for preventing downward movement of the head end of the rock lever.

5. An automatic gravity actuated golf ball teeing device including an inclined golf ball runway, a normally closed gate at the lower end of the runway to restrain the passage of a golf ball therefrom, a rock lever having a relatively short normally overbalanced head end, and a normally lighter tail end which is longer than the head end to provide a greater leverage than the head end, a golf ball tee member carried by the head end of the rock lever, a golf ball basket carried by the tail end of said rock lever, a golf ball magazine having a ball discharge chute, gate means normally restraining the passage of a golf ball to

the discharge chute, means operable upon the downward movement of the head end of the rock lever for opening the gate at the low end of the runway to release a ball therefrom onto said tee

5 member, means operable upon the upward movement of the tail end of the rock lever for actuating the gate means to release a ball from the magazine for gravitation over the discharge chute into said basket, the weight of the ball in the basket combined with the leverage of the tail end of the rock lever acting to overbalance the head end of the same to cause the head end to rise to raise the tee member to teeing position while the tail end moves downwardly, means operable as the tail end nears the limit of its downward movement to release a ball from the basket onto the high end of the runway for travel downwardly to the low end thereof against said gate, and releasable catch means operatively responsive to latching position by the weight of a golf ball resting upon the tee member for preventing the head end of the rock lever from moving downwardly under its overbalancing action.

6. An automatic gravity actuated golf ball teeing device as set forth in claim 5, including in the combination, means preventing the release of the releasable catch means when in catch position, and means responsive to the presence of a ball at the low end of the runway for rendering said 25 last mentioned means inoperative.

7. An automatic gravity actuated golf ball teeing device as set forth in claim 5, including therein guard means for preventing the golf ball from accidentally rolling from the tee member during 30 upward movement of the tee member to tee position.

8. In a golf ball teeing device, an inclined runway, a ball lifting lever, a pivoted gate member at the low end of the runway normally in a down ball obstructing position, a depressible actuating arm for lifting the gate member to raised ball releasing position and disposed in the path of downward movement of said lever, a tee member carried by said lever and adapted to receive a ball 40 from the runway when the lever is in down position and the gate is raised by engagement of the lever with the arm, means for actuating said lever from lowered position to raised position, and releasable catch means responsive to the weight of a ball present upon the tee member for securing the lever in raised position.

9. In a golf ball teeing device as set forth in claim 8, including a means acting to normally prevent the release of the catch means, and trip means responsive to the presence of a ball at the 55 low end of the runway for rendering the last means ineffective.

10. In a golf ball teeing device as set forth in claim 8, including a guard member movable with and relative to the up and down movements of the lever for preventing accidental upsetting of a ball from the tee member during the upward travel of the tee member to raised teed position.

LEONARD GALE.
